[57] CLAIM

The ornamental design for a handbag, as shown and described.

DESCRIPTION

FIG. 1 is a perspective view of the new design; FIG. 2 is the front view of the design of FIG. 1; FIG. 3 is the top view; FIG. 4 is the rear view thereof; FIG. 5 is the bottom view; and, FIG. 6 is an end view thereof, with the opposite end view being a mirror image thereof.

The strap in FIGS. 2, 3, 4, and 6, is shown broken away in the views to indicate indeterminate length.

The broken line showing of a strap in FIG. 1 is for illustrative purposes only and forms no part of the claimed design.
